UNITED STATES PATENT OFFICE.

VICTOR GABRIEL WERNER, OF BODEN, AND KARL HJALMAR WARFVINGE, OF STOCKHOLM, SWEDEN.

INDUCTIVE WIRELESS TELEPHONE SYSTEM FOR RAILROADS AND THE LIKE.

1,312,068.

Specification of Letters Patent. Patented Aug. 5, 1919.

Application filed May 10, 1916. Serial No. 96,491.

To all whom it may concern:

Be it known that we, VICTOR GABRIEL WERNER and KARL HJALMAR WARFVINGE, subjects of the King of Sweden, and residents, respectively, of Boden and of Stockholm, in the Kingdom of Sweden, have invented a new and useful Improvement in Inductive Wireless Telephone Systems for Railroads and the like, of which the following is a specification.

This invention relates to an inductive wireless telephone system for telephonic communication between a moving railroad train, or other vehicle, and a railroad station, or other stationary place, of the kind in which there is arranged on the train, or on the vehicle, a circuit comprising a microphone, a receiver and a source of current, which circuit is in inductive relation to another stationary circuit consisting of a single or double aerial conductor along the track and connected with a stationary telephone station. In an arrangement of this kind a very substantial reduction of the cost of erection will be attained if the telegraph or telephone wires usually present along the railway track may be used for the stationary circuit, or if, when during certain conditions this can not be done, the necessary special aerial conductor may be attached to the poles of the telegraph or telephone line. As the distance, however, between the train and the telegraph or telephone lines along the track is rather great, as a rule, and as this distance owing to traffic-technical reasons can not be reduced below a certain limit, it is necessary, in order to attain a practicable result, to use with the stationary telephone apparatus as well as with the moving apparatus, microphones of a certain kind, so-called strong-current microphones, which are capable of converting substantially greater quantities of energy into oscillations of speech frequency, than it is possible with ordinary microphones. The insertion of a strong-current microphone in the stationary circuit has the effect, however, that adjacent circuits are subjected to disturbances by induction which renders their use vastly more difficult, when telephoning to or from the train.

The present invention has for its object to eliminate this disadvantage, and, it is broadly characterized by this that the aerial conductor of the stationary circuit is di-

vided into two equal or approximately equal parts or branches connected in parallel and extending in opposite directions from the fixed station, which is connected with the point or points of union of the two branches of the conductor or conductors. The currents in the two branches which extend in opposite directions, may then by means of suitable regulation be made to exert an equally strong inductive influence, but in opposite directions so that the disturbing effects of induction on adjacent lines will become balanced. At the same time the advantage is attained that the influence of earth-currents on the two branches will equalize each other as regards the receiving apparatus, which fact is of particular importance when there is a single aerial conductor, the earth being used as return conductor.

If owing to local conditions, the two branches of the aerial conductor must be made of different lengths, or if for other reasons their inductive influences on adjacent lines become of different strengths, the desired freedom from disturbance may be obtained by connecting a fixed or a variable resistance in the branch which has the strongest disturbing influence. In the case that the inductive disturbances on adjacent conductors are of less consequence, the arrangement may be used for completely equalizing the disturbing effects of the earth-currents.

In the accompanying drawings Figures 1 to 12 show diagrammatically different embodiments of the invention. Fig. 1 shows an embodiment in which a single wire conductor especially erected, is used. Fig. 2 shows an embodiment in which the stationary circuit is formed by a section of an ordinary telegraph line wire, and Fig. 3 shows a similar embodiment with several stations. Fig. 4 shows a similar embodiment with a telegraph station included in the stationary circuit. Fig. 5 shows an embodiment using sections of a telegraph line wire grounded through condensers. Fig. 6 shows an embodiment using a double wire telephone line, and Fig. 7 illustrates a similar embodiment with a variable resistance. Fig. 8 shows another embodiment with a variable resistance in the line wires, and Fig. 9 shows a third modification of this embodiment. Fig. 10 shows an arrangement similar to Fig. 6

applied to several stations, and Fig. 11 shows an embodiment in which the fixed station is disconnected.

Fig. 1 shows an embodiment in which a single wire aerial conductor (A—B especially erected along the track is used, the two end points A and B of the same being grounded. Between the middle point C of the conductor and the earth the fixed telephone station is connected. This station is provided with a circuit-changer 1, by means of which either the strong-current microphone 2 with its source 3 of current or the receiver 4 may be connected into the circuit. The station on the train is provided in known manner with an induction frame 5, which is preferably mounted around the roof of a railroad car and which may be connected by means of a circuit-changer 6 either with the strong-current microphone 7 and its source 8 of current or with the receiver 9. As shown in the drawing the aerial conductor is divided into two equal branches C—A and C—B which are connected in parallel and which run in opposite directions from the fixed station, whereby the advantages referred to above are attained.

In the following figures the entire fixed station or stations are referenced D, D¹, D², etc., and the movable station (on the train) is referenced E, E¹, E², etc., for the sake of simplicity.

In the embodiment shown in Fig. 2 the stationary circuit is formed by a section A¹—C¹—B¹ of an ordinary single wire telegraph line T—T and of a special conductor 10—11—12 which is suitably erected on the other side of the track in regard to the telegraph line, the end points of the same being connected with the opposite points A¹ and B¹ of said line. About at the middle of the section the fixed station D is connected between the points C¹ and 11. The station D will thus be located in one of the diagonals of a Wheatstone bridge, the sides of which are formed by the lengths C¹—B¹, B¹—12—11, 11—10—A¹, and A¹—C¹, hence it becomes without current as regards the telegraph currents, provided that the resistances in the said sides are chosen properly. A variable resistance 13 is inserted in the length 11—12 in order to render possible regulation in this respect.

Fig. 3 illustrates this last described arrangement applied to a plurality of fixed stations D¹ each of which is connected in a diagonal of a Wheatstone bridge. The telegraph line T¹—T² forms two sides of each bridge, while the other two sides are formed by special conductors 110—112.

In Fig. 4 another modification of the arrangement according to Fig. 2 is illustrated which is proposed for the case that the section of the telegraph line A²—B² used in-

cludes a telegraph station F at the fixed telephone station D². The station F is shunted by means of two condensers 14 connected in series, and the telephone station D² is connected between the point of connection between these condensers and the middle point 211 of the conductor 210—212. Each of the connections A²—210 and B²—212 comprises a condenser 15. When the resistances of the different parts of the circuit have been properly chosen, the station D² becomes without current in regard to at least the most rapid variations in the telegraph currents.

In the arrangement according to Fig. 5 each of the two end points A³ and B³ of the section of the telegraph line T³—T³ used for telephoning, is grounded through a condenser 16 and 17. The choke coils 18 and 19 which are connected in the telegraph line beyond the points A³ and B³, and the condensers 20 and 21 which are inserted between points in the telegraph line beyond said choke coils, and the ground, serve in known manner for flattening the telegraph currents in the range A³—B³ and for preventing the telephone currents from extending beyond this range. The telephone station D³, which is connected in series with a condenser 22 inserted between the same and the telegraph line, is connected between the approximate middle point C³ of the section A³—B³ and the ground, and owing to the flattening of the telegraph currents it does not become disturbed by these currents to any appreciable degree. The variable resistance 23 serves for the same purpose as the resistance 13 shown in Fig. 2.

Fig. 6 shows how a double wire telephone line may be used for forming the stationary circuit, of which the length A⁴—C⁴—B⁴ forms the aerial conductor. At each end point of this length a choke coil 24 and 25 provided with an iron core is connected between the two wires of the telephone line, the middle points of these coils being grounded. At the station C⁴, which is located about at the middle of the length A⁴—B⁴, a similar choke coil 26 is connected between the wires of the telephone line, the fixed telephone station D⁴ being connected between the middle point of this coil and the earth. In conformity with the conditions of duplex connection of a telephone line between two fixed stations, and on account of the symmetry of the new circuit formed in regard to the two wires of the telephone line used, the new circuit becomes undisturbed as regards the ordinary traffic on the telephone line. Only a very small portion of the speech currents in the telephone line is short-circuited or led off through the choke coils, which offer only a very small resistance, however, to the currents in the new inductive circuit, as these currents divide

themselves on the two halves of the choke coils in such manner that the two branch currents equalize each other's induction in the iron cores of the coils.

5 Fig. 7 shows the same arrangement as Fig. 6, the only difference being that a variable resistance 27, which as regards action corresponds to the resistance 13 in Fig. 2, is inserted between the choke coil 25^a and 10 the earth.

According to Fig. 8 this variable resistance consists of two equal parts 28 and 29, each of which is connected to one wire of the double wire telephone line A⁵—C⁵—B⁵. 15 These resistances are preferably arranged in such manner that when there is no communication to or from the train, the resistances are short-circuited by means of the contacts 30 and 31, which are operated by means of 20 the hook 32 provided for the receiver of the fixed station D⁵.

In the arrangement according to Fig. 9 the variable resistance consists of two coils 33 and 34 bifilar wound on a common iron core, each of said coils being connected to one wire of the telephone line in such manner that the currents directed in opposite directions, which currents represent the ordinary traffic on the telephone line, equalize 30 each other's induction on the iron core. On the other hand, the coils form a powerful inductive resistance to one branch current of the new inductive circuit.

Fig. 10 illustrates the arrangement according to Fig. 6 applied to a plurality of stations D⁶, which are connected to the same double wire telephone line A⁶—B⁶. The stations are arranged in such manner that they are automatically short-circuited when not 40 in use. As soon as a receiver is lifted up at any station, a branched circuit is formed which extends to the adjacent station on each side, and the inductive action of which on adjacent lines is equalized, if desired by 45 means of variable resistances connected in the circuit. The stations are short-circuited by means of the hooks 35 for the receivers.

Fig. 11 illustrates an embodiment in which the fixed station D⁷ is disconnected, the primary winding 37 of a transformer being connected in its place between the middle point of the choke coil 36 and the earth, the secondary winding 38 of which transformer is connected between the two wires of the 55 double wire telephone line A⁷—B⁷, or to a special telephone line which connects the station D⁷ with another station D⁸. The currents induced in the stationary circuit by the circuits on the train will thus not 60 be received at the station D⁷, but will become transformed in the transformer 37, 38 and will thence be conducted by the double wire telephone line to a station on the railroad beyond the grounded section of the line, or 65 through a special telephone line to a tele-

phone station not on the railroad. By switching off the station D⁷ in this manner it is thus possible substantially to increase the range within which it is possible to obtain telephonic communication with the 76 moving railroad train.

Fig. 12 shows an embodiment of the invention which consists of a combination of the features illustrated in Figs. 2, 8 and 9 and in which a metallic conductor 10—11— 75 12 is substituted for the earth connection between the middle points of the choke coils.

We claim:

1. In an inductive wireless telephone system for railroads, the combination of a circuit on the train comprising a microphone, a receiver, and a source of current, and a stationary circuit in inductive relation to the first named circuit and comprising an aerial line along the railroad track connected to a 80 fixed telephone station, said aerial line being divided into two approximately equal branches connected in parallel and extending in opposite directions from the fixed telephone station, for the purpose of equalizing disturbing inductive effects on adjacent 85 circuits and also disturbances caused by earth-currents, substantially as described.

2. In an inductive wireless telephone system for railroads, the combination of a circuit on the train comprising a microphone, a receiver, and a source of current, a stationary circuit in inductive relation to the first-named circuit and comprising an aerial line along the railroad track connected to a fixed 95 telephone station, said aerial line being divided into two approximately equal branches connected in parallel and extending in opposite directions from the fixed telephone station, and a variable resistance connected to 100 one of said branches, substantially as, and for the purpose set forth.

3. In an inductive wireless telephone system for railroads, the combination of a circuit on the train comprising a microphone, a 110 receiver and a source of current, and a stationary circuit in inductive relation to the first named circuit and comprising a section of an aerial line along the railroad track and a conductor connected at its ends to the end 115 points of the said section, and a fixed telephone station connected between the approximate middle point of the said section and the approximate middle point of the said conductor, substantially as and for the 120 purpose set forth.

4. In an inductive wireless telephone system for railroads, the combination of a circuit on the train comprising a microphone, a receiver and a source of current, and a stationary circuit in inductive relation to the first named circuit and comprising a section of a double wire telephone line, choke coils connected between the two wires at the end 125 points of said section, the middle points of 130

4
said choke coils being connected together, a choke coil connected between the two wires at the approximate middle point of said section, and a fixed telephone station connected 5 between the middle of said choke coil and the connection between the middle points of the two choke coils first mentioned, substantially as and for the purpose set forth.

5. In an inductive wireless telephone system for railroads, the combination of a circuit on the train comprising a microphone, a receiver and a source of current, and a stationary circuit in inductive relation to the first named circuit and comprising a section 10 of a double wire telephone line, choke coils connected between the two wires at the end points of said section, the middle points of said choke coils being connected together, a variable resistance comprising two equal 15 parts one of which is connected to each wire of the section, a choke coil connected between the two wires at the approximate middle point of said section, and a fixed telephone station connected between the middle 20 of said choke coil and the connection between the middle points of the two choke coils first mentioned, substantially as and for the purpose set forth.

6. In an inductive wireless telephone system for railroads, the combination of a circuit on the train comprising a microphone, a receiver and a source of current, and a stationary circuit in inductive relation to the first named circuit and comprising a section 30 of a double wire telephone line, choke coils connected between the two wires at the end 35

points of said section, the middle points of said choke coils being connected together, a variable resistance comprising two equal parts one of which is connected to each wire 40 of the section, means for short-circuiting said variable resistance, a choke coil connected between the two wires at the approximate middle point of said section, and a fixed telephone station connected between the middle 45 of said choke coil and the connection between the middle points of the two choke coils first mentioned, substantially as and for the purpose set forth.

7. In an inductive wireless telephone system for railroads, the combination of a circuit on the train comprising a microphone, a receiver and a source of current, and a stationary circuit in inductive relation to the first named circuit and comprising a section 50 of a double wire telephone line, choke coils connected between the two wires at the end points of said section, the middle points of said choke coils being connected together, a variable resistance comprising two bifilar 55 wound coils one of which is connected to each wire of the section, a choke coil connected between the two wires at the approximate middle point of said section, and a fixed telephone station connected between the middle 60 of said choke coil and the connection between the middle points of the two choke coils first mentioned, substantially as and for the purpose set forth.

VICTOR GABRIEL WERNER.
